J. D. LANGDON

FLUID PRESSURE BOOSTER

Filed Nov. 14, 1927

Inventor
J. D. Langdon

UNITED STATES PATENT OFFICE.

JESSE D. LANGDON, OF LOS ANGELES, CALIFORNIA, ASSIGNOR TO LANGDON ENGINEERING CORPORATION, OF LOS ANGELES, CALIFORNIA.

FLUID-PRESSURE BOOSTER.

Application filed November 14, 1927. Serial No. 233,269.

The primary object of my invention is the provision of means for increasing the pressure delivery of fluid by the use of a hammer blow.

- 5 Another object of my invention is to provide a combination with a hammer actuated booster of means to prevent the distortion of the operating parts by the hammer blows used for operation.
- 10 A still further object of my invention is to provide means for the automatic refill of a hammer actuated or piston boosting device.

Other and further objects of my invention 15 will appear as the description proceeds, as illustrated by the accompanying drawings, which it is specifically understood are for the purpose of illustration only, and the shape and arrangement of parts may be 20 changed to suit the exigencies of their use, and the application of the invention.

Of the drawing:—The different parts consist of hammer pad —1—, piston rod or piston —2—, cylinder —3—, retaining cap —4—, main body —5—, piston stop —6—, coupling means or lugs —7—, check valve —8—, outlet —9—, outlet nipple —10—, outlet coupling —11—.

The operation of my device is substantially as follows: The check valve —8— is coupled to a pressure fluid delivering device (not shown) by means of coupling lugs —7—, or other convenient attaching means; the fluid entering through valve —8— is forced into cylinder —3— which is situated above the level of valve —8—, the shoulder —6— always maintaining the piston rod —2— at the right distance in relation to valve —8— so that the piston is forced away from shoulder —6— at all times by the pressure of fluid entering through valve —8—. The cylinder —3— being filled with fluid forcing the piston rod —2— into hammer pad —1— against retaining cap —4—, thus maintaining the device

in filled position at all times as long as the device is attached to the pressure fluid delivering means.

The device is coupled to any object into which it is desired to deliver fluid under pressure, the coupling means consisting of outlet nipple —10— and outlet coupling —11—.

When the booster has been coupled to the object into which or through which it is desired to deliver fluid, the hammer pad —1— is struck a blow with a hammer forcing fluid under excessive pressure through outlet —9— at the same time closing the inlet valve —8—, which automatically reopens 60 and allows cylinder —3— to refill, thus the device is ready for another hammer blow.

Having fully described my invention and that which is new, I claim:

1. A fluid pressure boosting device comprising a cylinder, a piston disposed within said cylinder, a hammer pad on one end of said piston, a retaining cap suitably disposed to allow for the movement of said piston in a cylinder body having a cylinder therein, said cylinder being so disposed within said main body that the piston traveling within said cylinder will at all times allow the entry of fluid under pressure against the end of said piston, together with a check 70 valved inlet to said cylinder and an outlet from said cylinder in combination with means to couple said pressure boosting device to a fluid pressure delivery line and an object to which it may be desired to deliver 80 fluid by means of said fluid pressure boosting device.

2. In a device described in claim 1, a shoulder at one end of a cylinder to prevent the piston in said cylinder from closing the 85 inlet passage to said cylinder.

In testimony whereof I have signed my name to this specification.

JESSE D. LANGDON.
